PHONOGRAPH RECORD HOLDING RACK OR SIMILAR ARTICLE

Rose M. Murat, San Clemente, Calif., assignor of one-fourth each to Elma M. Proctor-Wells and William H. Wells, Corona del Mar, Calif., and to Adolf R. Murat, San Clemente, Calif.

Filed Nov. 17, 1964, Ser. No. 82,651

Term of patent 14 years

(Cl. D33—3)

Fig. 2

Fig. 1

Fig. 3

FIG. 1 is a front perspective view of a phonograph record holding rack or similar article, showing my new design;

FIG. 2 is a top plan view as viewed along section line 2—2 in FIG. 1;

FIG. 3 is a bottom plan view.

The sides of a phonograph record holding rack or similar article, are plain and unornamented.

I claim:

The ornamental design for a phonograph record holding rack or similar article, as shown and described.
